The ornamental design for a ceramic tile sample display holder, as shown and described.

DESCRIPTION

FIG. 1 is a perspective view of a ceramic tile sample display holder showing my new design;

FIG. 2 is a front elevation view thereof;

FIG. 3 is a rear elevation view;

FIG. 4 is a right side elevation view, showing my new design, the left side elevation view being a mirror image;

FIG. 5 is a top plan view thereof; and,

FIG. 6 is a bottom plan view.
